UNITED STATES PATENT OFFICE.

EMIL JAGENBERG, OF DUSSELDORF, GERMANY, ASSIGNOR, BY MESNE ASSIGNMENTS,
TO THE CHEMICAL FOUNDATION, INC., A CORPORATION OF DELAWARE.

APPARATUS FOR WETTING THE PAPER CUT TO STRIPS FOR SPINNING PURPOSES.

1,367,050.

Specification of Letters Patent.

Patented Feb. 1, 1921.

Application filed October 18, 1916. Serial No. 126,322.

To all whom it may concern:

Be it known that I, EMIL JAGENBERG, a subject of the German Emperor, and residing at Dusseldorf, Germany, have invented 5 certain new and useful Improvements in 5 Apparatus for Wetting the Paper Cut to Strips for Spinning Purposes, of which the following is a statement.

The present invention relates to a method 10 and apparatus by which uniform wetting and keeping moist strips of paper, wound in reels, and intended for spinning purposes are obtained.

The wetting mechanism has been dia- 15 grammatically shown in the accompanying drawing.

The web of paper *p* is conducted over rollers and is cut by circular blades *m*, while in dry condition, into a plurality of strips, which are then conducted over a guide roll and a pressing roll *a* to the reel *w*. As the paper is cut while dry, the narrow strips are easily and accurately cut, which strips if cut wet would tend to avoid and clog up 25 the cutters. Furthermore the paper cut in dry condition will not run out of line so easily, and the individual rolls may therefore be more easily detached from each other, whereby waste is avoided. By the 30 paper being applied dry and wetted only thereafter it will lie smoothly layer upon layer and have an even tension.

In front of the reel is disposed a water tank *b* in which a number of neighboring 35 pipes *r* dip, which are open at top and bottom. At the top a pipe *h* is disposed beside the pipes *r*, said pipe *h* having apertures, which are so arranged that they are close to the upper end of the pipes *r*. The pipe 40 *h* communicates with a supply pipe for compressed air or the like, so that such air emerges from the apertures *o*, whereby in known manner water is sucked up through the pipes *r* and is sprayed against the winding on reel *w*.

Beneath the reel *w* is a sheet metal plate *e*, by means of which the water is more

effectively conducted to the roll of paper and is prevented from passing beneath the same and wetting the operator of the ma- 50 chine and articles standing near by. This plate *e* is hinged at *d*, and is pressed by means of weights or springs with its rear edge against the reel *w*. It will, therefore, yield by itself downward, when the size of 55 the roll of paper increases. Any liquid which may collect in form of drops on the plate will be conducted by the same to a tank *g*. Beneath the blades *m* another plate *c* is provided, which is intended to protect 60 said blades against spattering water.

By the new arrangement, by means of which the water is formed into a cloud-like spray and is simultaneously blown against the strips of paper on the winding reels, 65 whereupon the latter are immediately reeled, not only a very uniform wetting is obtained, but at the same time the desired degree of moisture is maintained in the paper strips.

I claim:

An apparatus for wetting strips of paper wound on reels for spinning purposes, and maintaining them moist, comprising a water tank, pipes dipping into said tank, a pipe 75 disposed along the top of said dipping pipes and having apertures close to the upper openings of said dipping pipes, means for sending a blast of compressed air or the like through said pipe, said pipe so disposed 80 that the water sucked by such blast and diffused is directed against the winding reel, a hinged plate, means for pressing said hinged plate with its free end against the roll of paper, said plate adapted to direct 85 the spray of water against said roll and prevent its passing beneath.

In testimony whereof I have hereunto signed my name in the presence of two sub-scribing witnesses.

EMIL JAGENBERG. [L.S.]
